L. R. MILLER

STARTING ATTACHMENT FOR HYDROCARBON BURNERS

Filed April 18, 1923

FIG. 1.

FIG. 2.

FIG. 3.

Inventor
LESLIE R. MILLER.

By A.B. Bowman

Attorney

UNITED STATES PATENT OFFICE.

LESLIE R. MILLER, OF SAN DIEGO, CALIFORNIA.

STARTING ATTACHMENT FOR HYDROCARBON BURNERS.

Application filed April 18, 1923. Serial No. 632,860.

To all whom it may concern:

Be it known that I, LESLIE R. MILLER, a citizen of the United States, residing at San Diego, in the county of San Diego and State 5 of California, have invented a certain new and useful Starting Attachment for Hydrocarbon Burners, of which the following is a specification.

My invention relates to hydrocarbon 10 burner starting attachments; and the objects of my invention are: first, to provide a starting apparatus of this class for burners in which steam is mixed with the fuel to aid combustion or in which steam is used to vaporize liquid fuel and mix with the same to 15 facilitate combustion; second, to provide an apparatus of this class for quickly generating steam for hydrocarbon burners of the class mentioned; third, to provide an apparatus 20 of this class in the form of a coil in which paper, wood, or other readily combustible material may be placed for generating steam in the same; fourth, to provide an apparatus of this class which, when 25 steam is generated in the coil thereof and conducted to the hydrocarbon burner, will ignite the gases issuing therefrom, which ignited gases will play upon the coil, thus continuing to generate steam in the same; fifth, 30 to provide an apparatus of this class which, when used in connection with a boiler, may be shut off, disconnected and removed from the fire box of the boiler when sufficient steam has been generated in the boiler to 35 conduct steam to the burner; sixth, to provide an apparatus of this class which will generate sufficient steam to operate the fuel oil pump for the burner until steam is generated in the boiler, and seventh, to provide 40 a novelly constructed apparatus of this class and an apparatus which is particularly simple and economical of construction, durable, efficient, and which will not readily deteriorate due to the intense heat of the burner 45 and which will not readily get out of order.

With these and other objects in view, as will appear hereinafter, my invention consists of certain novel features of construction, combination and arrangement of parts 50 and portions as will be hereinafter described in detail and particularly set forth in the appended claims, reference being had to the accompanying drawings and to the characters of reference thereon, which form a part 55 of this application, in which:

Figure 1 is a sectional elevational view of a boiler, taken substantially through the middle thereof, in which a hydrocarbon burner is used to supply the heat and showing my apparatus positioned in the fire box 60 thereof and connected to a water supply main and to the burner; Fig. 2 is an enlarged, fragmentary, sectional elevational view thereof with the section taken through the middle of the coil, showing wood positioned therein for firing the same, and Fig. 3 is a sectional view thereof taken through 3—3 of Fig. 2.

Like characters of reference refer to similar parts and portions throughout the several views of the drawings.

In Figure 1 of the drawings I have shown a conventional shell boiler 1, supported and enclosed by the conventional masonry structure 2. Below the forward end of said boiler 75 is provided the fire box 3 into which is directed the flame from the hydrocarbon burner 4, which is positioned in the burner opening 2^a of the structure and supported by the front shell 5 of the structure. Through 80 the front wall of the masonry structure 2 and below the burner opening 2^a is provided another opening 2^b for removing ashes and the like and which is made sufficiently large for the introduction of the steam generating 85 unit or coil 6 therethrough into the fire box 3, substantially as shown in Fig. 1 of the drawings. The steam generating coil 6 is preferably made from a relatively heavy 90 tubing, helically formed so that paper, wood, oily waste or other readily combustible material may be readily positioned therein for heating the same. Said coil 6 is provided with tubular conductors 7 and 8 extending therefrom and through the opening 2^b, one 95 of which conductors is provided at its extended end with a hose fitting, which is adapted to be connected to a water main 9 by means of a hose 10, a needle valve 19 being positioned in the line between the water 100 main and the coil 6. The other conductor 7, which is connected to the remote end of said coil and extends through the middle thereof, is adapted to be connected to the steam line 11, which communicates with the 105 burner, by means of the union 12. Said steam line is also connected to the upper portion of the steam boiler 1 by means of the conductor 13. Valves 14 and 15 are provided near the adjacent ends of the conduct 110

2

tors 11 and 13, the conductor connecting said valves being connected to the conductor 16 which is connected to the burner 4, and another conductor 20 extending therefrom being adapted to be connected to a fuel oil pump for said burner. Said valves are provided so that the one provided at the end of the line connected with the boiler may be closed off when the burner is connected up 10 with the steam generating coil 6 and the valve 14 may be closed when sufficient steam is generated in the boiler to supply the burner. A valve 18 is provided on said burner to adjust the fuel thereto from the 15 fuel conductor 17 connected to a fuel supply line.

To start the burner the coil 6 is positioned and connected as described and a fire kindled in or around the coil. As the 20 coil is sufficiently heated, the needle valve 19 is opened and water allowed to flow through the heated tubes, generating steam instantly, which steam is conducted to the burner for vaporizing and mixing with the 25 fuel oil, which vaporized fuel oil is then ignited by the fire in or around the coil.

Though I have shown and described a particular construction, combination and arrangement of parts and portions, I do not 30 wish to be limited to this particular construction, combination and arrangement, but desire to include in the scope of my invention, the construction, combination and arrangement substantially as set forth in the 35 appended claims.

It is obvious from this construction that 40 there is provided a starting apparatus for hydrocarbon burners in which steam is mixed with the fuel and used to atomize liquid fuel and which will start the burner in a relatively short period of time; that there is provided an apparatus of this class in which a coil is used for generating the steam for the burner, which coil is adapted 45 to be positioned in the fire box of the boiler structure and adapted to be disconnected and readily removed therefrom when sufficient steam has been generated in the boiler to supply the burner; that there is provided 50 an apparatus of this class in which paper, wood or other readily combustible material may be placed within the coil for heating the same, and which is so positioned in the fire box that the flame of the burner will be directed thereon so as to continuously generate steam before steam is generated in the 55 boiler for said burner; that there is provided a novelly constructed starting apparatus for hydrocarbon burners, and an apparatus of this class which is very simple and economical of construction, durable, efficient and which will not readily deteriorate due to the intense heat from the hydrocarbon burner and which will not readily 60 get out of order.

Having thus described my invention, what I claim as new and desire to secure by Letters Patent, is:

1. In an attachment for starting hydrocarbon burners, the combination with a 70 hydrocarbon burner of a hollow, continuous steam generating unit, adapted to be quickly positioned in the fire box in which the flame of said burner is directed, and means for readily and quickly connecting and disconnecting said steam generating unit with a water main and a steam line connected to said burner whereby the generator may be quickly removed as soon as the fire is started. 75

2. In an attachment for starting hydrocarbon burners, the combination with a 80 hydrocarbon burner of a hollow, helical, tubular, steam generating coil, adapted to be quickly positioned in the fire box into which the flame of said burner is directed, and means for readily and quickly connecting and disconnecting said coil with a water 85 main and said burner whereby the generator may be quickly removed as soon as the fire is started. 90

3. In an attachment for starting hydrocarbon burners, the combination with a 95 hydrocarbon burner of a helical, tubular coil in which is adapted to be placed non-liquid hydrocarbon and which coil is adapted to be positioned in a fire box into which the flame of said burner is directed, conductors extending from said coil, hose means connecting one of said conductors with a water main, and a union connecting the other of 100 said conductors with said burner whereby the generator may be quickly removed as soon as the fire is started. 105

4. In an attachment for starting hydrocarbon burners, the combination with a 110 hydrocarbon burner of a hollow, continuous steam generating unit adapted to be positioned in the fire box in which the flame of said burner is directed, conductors extending from said steam generating unit, hose means connecting one of said conductors with a water main, and a union connecting the other of said conductors with said burner whereby the generator may be quickly removed as soon as the fire is started. 115

5. In an attachment for starting hydrocarbon burners, the combination with a 120 hydrocarbon burner of a removable steam generating unit, adapted to be positioned in the fire box into which the flame of said burner is directed, and means in connection therewith for readily and quickly connecting and disconnecting said coil with a water main and said burner whereby the generator may be quickly removed as soon as the fire 125 is started.

6. In an attachment for starting hydrocarbon burners, the combination with a 130 hydrocarbon burner of a removable steam generating unit, adapted to be positioned in

the fire box into which the flame of said burner is directed, means in connection therewith for readily and quickly connecting and disconnecting said coil with a water main and said burner, and valve means for regulating the flow of water to said steam generating unit and regulating the flow of steam therefrom whereby the generator may be quickly removed as soon as the fire is started.

7. In an apparatus for starting hydrocarbon burners, the combination with a hydrocarbon burner of a steam generating

unit positioned in front of said burner and provided with extended conductors, and means in connection therewith for readily connecting and disconnecting said steam generating unit with a water main and a steam line connected to said burner whereby the generator may be quickly removed as soon as the fire is started.

In testimony whereof, I have hereunto set my hand at San Diego, California, this 11th day of April, 1923.

LESLIE R. MILLER.
